UNITED STATES PATENT OFFICE.

CHESTER T. ALLCUTT, OF PITTSBURGH, PENNSYLVANIA, ASSIGNOR TO WESTINGHOUSE ELECTRIC AND MANUFACTURING COMPANY, A CORPORATION OF PENNSYLVANIA.

PROTECTIVE DEVICE.

Application filed August 15, 1919. Serial No. 317,686.

To all whom it may concern:

Be it known that I, CHESTER T. ALLCUTT, a citizen of the United States, and a resident of Pittsburgh, in the county of Allegheny and State of Pennsylvania, have invented a new and useful Improvement in Protective Devices, of which the following is a specification.

My invention relates to discharge gaps as used, for example, in lightning arresters, and it has for its object to provide apparatus of the character designated that shall operate selectively in permitting current passage therethrough, preferably with a low impulse ratio or, in other words, permitting the passage of high frequency currents at equal or lower voltage than currents of normal frequency while also permitting the passage of currents of high voltage at any frequency.

Another object of my invention is to produce a structure of the character indicated that shall be largely independent of rain.

In my copending application, Serial No. 216,088, relating to protective devices and assigned to the Westinghouse Electric & Manufacturing Company, is described a selective discharge gap consisting of two spaced discharge members and an auxiliary electrode disposed therebetween and connected to the two discharge members through impedance members of dissimilar character, so that while the potential of the auxiliary electrode is maintained at substantially the potential of the immediately adjacent electrostatic fields at normal frequency, it is changed to a different potential at any other frequency on account of the dissimilar potential drops in the two impedance devices upon a change in frequency.

It is now a known fact that the discharge potential of a spark gap varies with the atmospheric conditions, being considerably less when the gap is exposed to rain than when dry.

My present invention consists of the combination of an auxiliary spark gap with the previously described selective discharge device in such manner that the potential of the auxiliary electrode is raised to substantially that of one of the discharge members or higher when the auxiliary gap breaks down. The auxiliary spark gap is provided with a protecting member so that the elec-

trodes thereof and the space intermediate the electrodes will be protected from the rain, thereby maintaining substantially the same breakdown voltage at all times.

In the accompanying drawings, Figs. 1 to 4, inclusive, indicate purely diagrammatic forms of my invention; and Fig. 5 is partially a structural and partially a diagrammatic view of the preferred form of my invention of which Fig. 4 is the electrical equivalent.

Disturbances of abnormally high frequency are particularly destructive because of their tendency to cause a very high electromotive force to build up between adjacent turns of electrical windings and it is desirable to discharge such abnormal disturbances even before they have attained line voltage. Also, disturbances of normal frequency and abnormal potential are apt to occur on the line and are equally dangerous to apparatus connected thereto. These two types of disturbances, or combinations thereof, constitute the chief sources of trouble in protecting electrical apparatus connected to a distributing system. My present invention is adapted to eliminate all types of disturbances, irrespective of the character thereof, and to operate in the same manner irrespective of whether or not the device is exposed to rain.

Referring to the drawings for a more detailed understanding of my invention I show in Fig. 1 a line wire 6 connected to a horn type discharge member 7. A similar horn-type discharge member 8 is mounted in spaced relation thereto and is connected to ground at 9, either directly or through an electrolytic arrester 10, as desired. A small antenna 11 is mounted between the horns 7 and 8, this antenna being connected to the horn 7 through an inductive reactor 12 and a condensive reactor 13 connected in series relationship, and through a spark gap 14 connected, in parallel relationship therewith, and to the horn 8 through a condensive reactor 15. The spark gap 14 comprises two electrodes 16 and 17 and a shield 18, whereby the electrodes are protected from the rain.

The antenna 11 is disposed in that portion of the electrostatic field intermediate the discharge members 7 and 8 that is of the same potential as a connection 11^a between the condenser 15 on one side and the

condenser 13 and the inductive reactor 12 on the other side.

Assuming that the connection 11^a is maintained at a potential midway between that of the members 7 and 8 by means of the condensers 13 and 15 and the inductive reactor 12, and that the antenna is disposed in an electrostatic field the potential of which is equal to that of the connection 11^a, it is desirable that the length of the gap 14 be such that its dry breakdown voltage is equal to one-half the wet breakdown voltage of the gap formed by the members 7 and 8. Under these conditions a disturbance of normal potential and of abnormal frequency will cause the relative potential drop across the condenser 15 to decrease, thus causing the potential of the antenna to approach that of the discharge member 8 and causing substantially the entire potential of the line 6 to be impressed across the gap between the members 7 and 11 and therefore across the gap 14 which is connected in parallel relationship therewith. Since the breakdown voltage of the gap 14 is the same for either wet or dry weather and is equal to one-half the wet breakdown voltage of the gap between the discharge members 7 and 8, it follows that in dry weather the gap 14 will break down before a discharge passes between the antenna 11 and the member 7. Breakdown of the gap 14 immediately causes the potential of the antenna 11 to approach that of the discharge member 7 thus impressing substantially full line potential across the gap between the members 8 and 11, resulting in a discharge therebetween. The discharge between the members 8 and 11 causes an ionization of the surrounding medium and the member 7 being of a higher potential than is the antenna 11, the discharge is transferred thereto. The fact that a single discharge gap offers less opposition to the flow of current than does a plurality of spark gaps of substantially equal total breakdown voltage causes the main current to pass directly from the horn 7 to the horn 8 and the discharge across the gap 14 ceases. The arc is extinguished by rising on the horn members in the usual manner. In wet weather, the initial discharge may occur either between the members 7 and 11 or across the gap 14, their breakdown voltages being equal.

Assuming the gaps to be of the lengths described, a disturbance or surge of abnormal potential and normal frequency will result in the point 11^a being maintained at a potential midway between that of the members 7 and 8, which results in a drop of potential between the members 7 and 11 equal to that across the gap 14. The breakdown voltage of the gap 14 being lower than that of the gap between the members 7 and 11, except

when the latter is wet, under which conditions the two breakdown voltages are equal, so that, in wet weather the two gaps break down at the same time and in dry weather the gap 14 breaks down first. The antenna 11 is thereby raised to the potential of the discharge member 7, inducing an initial discharge between the members 8 and 11, and a final discharge between 7 and 8, as described. The fact that the gap 14 is protected from the rain and therefore independent thereof and the fact that this gap insures that a discharge will occur upon a slight overvoltage renders the entire device independent of the rail.

In Fig. 2 I show a modification of my invention in which the inductive reactor 12 of Fig. 1 is replaced by a noninductive resistor 19 which, together with the condensive reactor 13, is connected in parallel relationship with the spark gap 14. The difference in the effect of the change of frequency upon the members 15, and 19 and 13, will produce the desired selectivity of frequency necessary for the desired operation of the device at abnormal frequency. The spark gap 14 will produce the desired effect of rendering the breakdown at abnormal potentials largely independent of atmospheric conditions.

In Fig. 3 I show the antenna 11 connected to the discharge member 7 through an inductive reactor 12 and a condensive reactor 13 similar to that as shown in Fig. 1. A noninductive resistor 20 is connected in series relationship with the spark gap 14. This serves to limit the flow of current across the gap 14 thereby reducing the size of the gap structure and shelter necessary.

In Fig. 4 I show a condensive reactor 15 connected between the antenna 11 and the discharge member 8 and a non-inductive resistor 19 and a condensive reactor 13 connected in series relationship between the antenna 11 and the discharge member 7. The spark gap 14 is connected in series relationship with an inductive reactor or choke coil 22, which circuit is connected in parallel relationship with the inductive reactor 19 and the condensive reactor 13.

It will be understood by those skilled in the art that by reason of having the choke coil in series with the gap 14, as shown in Fig. 4, the current passing across the gap 14 and through the choke coil 22 charges the condenser 15, before breaking down the gap between the members 8 and 11, to substantially twice the potential of the charging current, as is a well known fact in connection with condensers and inductive reactances connected in series. The antenna 11 being connected to the condenser 15, the potential thereof is raised to a value higher than that of the member 7, insuring that a discharge be induced between the members 8 and 11.

In Fig. 5 I illustrate the preferred form of the apparatus indicated diagrammatically in Fig. 4 which comprises having the horn gap discharge member 7 mounted upon a corrugated insulating pillar 23, resting, in turn, upon a pillar type insulator 24, which comprises a series of conducting members 25 separated by insulating members 26, as is well known in the art.

10 The discharge member 7 is provided with a discharge terminal 27 of a hemispherical contour at its base, said member facing the antenna 11 which is supported at and is connected to an intermediate point in the pillar type insulator 24. An insulator 28 mounted upon a conducting supporting base 29 carries a conductor 30 which supports a hemispherical discharge member 31 in a position opposite to the discharge member 27 and

15 also carries a corrugated insulating member 32 upon which is mounted a horn member 33 disposed so as to be opposite the horn member 7. The purpose of the horn 33 is to receive the discharge as it rises from the members 27 and 31. The line wire 6 is connected to the upper conducting member of the pillar type insulator 24 through a non-inductive resistor 34 and the horn member 33 is similarly connected to the conductor 30

20 through a resistor 35, the conductor 30 being connected to ground 9 either directly or through an electrolytic arrester 10, as desired. The pillar type insulator 24 provides a series of small condensers, a portion of

25 which are connected between the base of the antenna 11 and a resistor 34, and the remainder of which are connected between the base of the antenna and the supporting member 29. The insulator 28 also serves as a condenser between the support 29 and the conductor 30. The spark gap structure 14 comprises an electrode 16 mounted within a conducting shield member 18, both of which are mounted upon a member 36 forming one

30 end of the horn member 7 and connected to the line wire 6. An electrode 17 is disposed in spaced relation to the electrode 16 and is supported upon a choke coil or inductive reactor 22 which, in turn, is mounted upon a supporting member 37, the opposite end of which serves as a support for the antenna 11.

Throughout this specification and in the appended claims, I desire the expression "discharge connection" to be defined as "ground or a circuit to which it is desired that a source of supply be connected when the discharge gap breaks down."

While I have shown several forms of my invention it will be understood by those skilled in the art that it is not so limited but is susceptible of various minor changes and modifications without departing from the spirit thereof, and I desire, therefore, that only such limitations shall be placed there-

upon as are imposed by the prior art or are specifically set forth in the appended claims.

I claim as my invention:

1. In an electrical-discharge-gap apparatus, the combination with two discharge members mounted in spaced relation to each other and connected to a supply circuit, of means dependent on the frequency or on the potential of said supply circuit for insuring that a less nearly uniform potential gradient exists between the said discharge members at abnormal frequencies and potentials than under normal conditions. 70
2. In electrical-discharge-gap apparatus, the combination with two discharge members mounted in spaced relation to each other and connected to a supply circuit, of means dependent on the frequency or on the potential of said supply circuit for modifying the shape of the electrostatic field between said discharge members. 80
3. In electrical-discharge-gap apparatus, the combination with two discharge members mounted in spaced relation to each other and connected to a supply circuit, of an auxiliary electrode mounted adjacent said discharge members and means dependent on either the frequency or the potential of said supply circuit for regulating the potential of said auxiliary electrode. 90
4. In electrical-discharge-gap apparatus, the combination with two discharge members mounted in spaced relation to each other and connected to a supply circuit, of an auxiliary electrode mounted adjacent said discharge members, and means connecting said electrode and one of said discharge members embodying means responsive to changes of frequency and to abnormally high potentials. 100
5. In electrical-discharge-gap apparatus, the combination with two discharge members mounted in spaced relation to each other and connected to a supply circuit, of an auxiliary electrode mounted adjacent said discharge members, and means connecting said electrode and one of said discharge members embodying impedance and an over-voltage breakdown device. 110
6. In electrical-discharge-gap apparatus, the combination with two discharge members mounted in spaced relation to each other and connected to a supply circuit, of an auxiliary electrode mounted adjacent said discharge members, and means connecting said electrode and one of said discharge members embodying an inductive reactor and means provided with a spark gap connected in parallel relationship. 115
7. In electrical-discharge-gap apparatus, the combination with two discharge members mounted in spaced relation to each other and connected to a supply circuit, of an auxiliary electrode mounted adjacent said discharge members, and means connect- 125
8. In electrical-discharge-gap apparatus, the combination with two discharge members mounted in spaced relation to each other and connected to a supply circuit, of an auxiliary electrode mounted adjacent said discharge members, and means connect- 130

- 5 ing said electrode and one of said discharge members embodying a condensive reactor, and means connecting said electrode to the other of said discharge members embodying 10 an inductive reactor and means provided with a spark gap connected in parallel relationship.
- 6 8. The combination with an electrical-discharge-gap device comprising two spaced 10 discharge members one of which is connected to a source of supply and the other of which is connected to a discharge connection, of an auxiliary electrode mounted intermediate said discharge members, and 15 connected to said supply connected discharge member through means provided with a spark gap and an inductive reactor connected in series relationship, and connected to said other discharge member 20 through a condensive reactor. 75
- 7 9. In electrical-discharge-gap apparatus, the combination with two discharge members mounted in spaced relation to each other and connected to a supply circuit, of an auxiliary electrode mounted intermediate 25 said discharge members, and means connecting said electrode and one of said discharge members embodying an inductive reactor and means provided with a spark gap 30 connected in parallel relationship, said spark gap means being protected from the weather. 80
- 8 10. In an electrical discharge device, the combination with a conducting member, of two insulators mounted therupon, discharge members mounted upon said insulators and jointly forming a discharge gap, an auxiliary electrode mounted in proximity to said gap, and connections from said auxiliary 35 electrode to each of said discharge members through the condensive reactance provided by each of said insulators and its associated conducting members, respectively, and an additional connection intermediate said auxiliary electrode and one of said discharge members embodying means provided 40 with a spark gap. 90
- 9 11. In electrical-discharge-gap apparatus, the combination with two discharge members mounted in spaced relation to each other and connected to a supply circuit, of an auxiliary electrode mounted adjacent 45 said discharge members, and means connecting said electrode to one of said discharge members embodying impedance and additional means connecting said electrode to the other of said discharge members embodying impedance of a character dissimilar to that previously mentioned, and an auxiliary spark gap device connected between 50 said electrode and one of said discharge members. 105
- 10 12. In an electrical-discharge device, the combination with two discharge members mounted in spaced relation to each other, 55 one of said members being connected to a supply circuit and the other being connected to a discharge connection, of an auxiliary electrode mounted adjacent said discharge members and connected to one of said discharge members through means provided with a spark gap and an inductive reactance connected in series relationship, and to the other discharge member through a condensive reactance. 110
- 11 13. In discharge gap apparatus, the combination with two spaced discharge electrodes connected to a source of supply, of means for normally maintaining the potential gradient between said electrodes substantially uniform and for causing said field to be less uniform at abnormal potentials of said supply circuit. 115
- 12 14. In discharge gap apparatus, the combination with two spaced discharge electrodes connected to a source of supply, of means dependent on the potential of said source of supply for determining the uniformity of the potential gradient adjacent said electrodes. 120
- 13 15. In discharge gap apparatus, the combination with two spaced discharge electrodes connected to a supply circuit, of means dependent on the potential of said supply circuit for insuring that a less nearly uniform potential gradient exists adjacent said electrodes at abnormal potentials than at normal potential. 125
- 14 16. In discharge gap apparatus, the combination with two spaced discharge electrodes connected to a supply circuit, of means dependent on the potential of said supply circuit for modifying the electrostatic field between said electrodes. 130
- 15 17. In discharge gap apparatus, the combination with two spaced discharge electrodes, of an auxiliary electrode mounted intermediate said discharge electrodes, and means connecting said auxiliary electrode to one of said discharge electrodes provided with a spark gap. 135
- 16 18. In discharge gap apparatus, the combination with two spaced discharge electrodes, of an auxiliary electrode mounted intermediate said discharge electrodes, and means connecting said auxiliary electrode to one of said discharge electrodes provided with a spark gap and to the other of said discharge electrodes comprising a capacitive reactor. 140
- 17 19. The combination with two spaced discharge electrodes, and an auxiliary electrode mounted in the path of discharge between said discharge electrodes, of means connecting said auxiliary electrode to one of said discharge members embodying an inductive reactor and an auxiliary device provided with a spark gap. 145

20. The combination with two spaced discharge electrodes, and an auxiliary electrode mounted adjacent said discharge electrodes, of means connecting said auxiliary electrode to one of said discharge members embodying an inductive reactor and an auxiliary device provided with a spark gap connected in series relationship. 40
21. In discharge gap apparatus, the combination with two spaced discharge electrodes, of an auxiliary electrode mounted intermediate said discharge electrodes, and means connecting said auxiliary electrode to one of said discharge electrodes comprising a device provided with a protected spark gap. 45
22. In discharge gap apparatus, the combination with two spaced discharge electrodes, of an auxiliary electrode mounted intermediate said discharge electrodes, and means connecting said auxiliary electrode to one of said discharge electrodes comprising a device provided with a spark gap protected from the weather. 50
23. In an electrical discharge device, the combination with two discharge members mounted in spaced relation to each other, one of said members being connected to a source of supply and the other to a discharge connection, and an auxiliary electrode mounted adjacent said discharge members and connected to one of said discharge members through condensive reactance and to the other of said discharge members by means of two parallel circuits one of which embodies a condensive reactor and a non-inductive resistor connected in series relationship and the other of which embodies a device provided with a spark gap and an inductive reactor connected in series relationship. 55
24. In an electrical-discharge-gap device, the combination with a main gap device consisting of two spaced discharge members, of an auxiliary device provided with a spark gap connected in parallel relationship with a portion of said gap device. 60
25. In an electrical-discharge-gap device, the combination with two spaced main discharge members, of an auxiliary electrode mounted intermediate said main discharge members and connected thereto, and means whereby said auxiliary electrode may be raised to a potential higher than that of either of said main discharge members. 65
26. In an electrical-discharge-gap device, the combination with two main electrodes mounted in spaced relation to each other, an auxiliary electrode mounted adjacent said main electrodes and connected to one of said main electrodes by a connection comprising capacitance, of means for changing the capacitance of said connection under predetermined voltage conditions. 70
27. In an electrical-discharge-gap device, the combination with two main electrodes mounted in spaced relation to each other, an auxiliary electrode mounted adjacent said main electrodes and connected to one of said main electrodes by a connection comprising capacitance, of means for increasing the capacitance of said connection when the voltage exceeds predetermined limits. 75
- In testimony whereof, I have hereunto subscribed my name this 1st day of August, 1919.

CHESTER T. ALLCUTT.
